CLAIM

The ornamental design for an eye energizing device, as shown and described.

DESCRIPTION

FIG. 1 is a front elevational view of an eye energizing device, showing my new design;

FIG. 2 is a rear elevational view thereof;

FIG. 3 is a left side view thereof;

FIG. 4 is a right side view thereof;

FIG. 5 is a top plan view shown at an enlarged scale thereof;

FIG. 6 is a bottom plan view shown at an enlarged scale thereof; and,

FIG. 7 is a perspective view thereof.

The broken lines shown in figures are for the purpose of illustrating portions of the eye energizing device, which form no part of the claimed design.

1 Claim, 6 Drawing Sheets---
